UNITED STATES PATENT OFFICE.

MIKEL LAVIGNE, OF WORCESTER, MASSACHUSETTS, ASSIGNOR TO S. MALOUF PATENT COMPANY, INC., OF WORCESTER, MASSACHUSETTS, A CORPORATION OF MASSACHUSETTS.

SPINNING SPINDLE.

Application filed September 16, 1921, Serial No. 501,157. Renewed October 31, 1924.

To all whom it may concern:

Be it known that I, MIKEL LAVIGNE, a citizen of the United States, residing at Worcester, in the county of Worcester and State of Massachusetts, have invented certain new and useful Improvements in Spinning Spindles, of which the following is a specification.

This invention relates to improvements in spindles as used in connection with spinning apparatus.

The primary object of the invention is the provision of a spindle for receiving a bobbin, and including certain novel bearing and lubricating means.

A further object of the invention is the provision of a spinning spindle in which the parts cooperate in practical manner to provide an assembled structure, in which the various parts thereof are easy of access and adjustment.

Specifically, the invention comprehends the provision of apparatus in which the spindle proper is supported within a suitable bolster in such manner as to provide for the accurate adjustment of the spindle and bolster to compensate for wear. The invention further embodies a lubricating system, in which the oil supply thereof is protected from dust, dirt and the like, provision being made for easy access to a lubricant reservoir for supplying the same.

Other objects and advantages will be apparent during the following detailed description.

In the accompanying drawings, wherein similar reference characters designate corresponding parts throughout the several views,

Figure 1 is a side elevation of the improved spindle apparatus.

Figure 2 is a vertical cross sectional view taken through the spinning spindle, and showing various details of construction.

Figure 3 is a horizontal cross sectional view taken on the line 3-3 of Figure 2.

Figure 4 a horizontal cross sectional view taken on the line 4-4 of Figure 2.

Figure 5 is a fragmentary cross sectional view of a lower end of the spindle casing.

Figure 6 is a side elevation of a spindle bolster used in the improved spinning spindle.

Figure 7 is a fragmentary side elevation of certain details of the improved spindle,

and showing the same in a manually adjusted position with respect to said parts as indicated in Figures 1 and 2. In the drawings, wherein for the purpose of illustration is shown the preferred embodiment of my invention, the letter A designates a rail, upon which the supporting casing B is mounted. A spindle C is provided rigid with the whirl D, for mounting on the casing B, a bolster E being provided in the casing B for receiving said spindle C. Adjustable means F is provided for rotatably supporting the bearing end of the spindle C.

The spindle casing B includes the head 10, which is provided with a depressed annular groove 11 therein, provided as a reservoir for lubricating material. A portion 12 of the casing B extends upwardly from the head 10 and is provided with a smooth aperture 13 axially in the upper end thereof, which communicates with the interior passageway 14 of said casing B. The portion 15 of casing B which depends from the head 10 is provided for a short distance below said head 10 with the external screw threads 15^a adapted for receiving an adjusting nut 16 and bearing washer 17, whereby the casing B may be clamped to the rail A intermediate the head 10 and the nut 16. The extreme lower end of the portion 15 is provided with the internally screw threaded inlet opening 19, which aligns with the passageway 14. Suitable slots 20 are provided diametrically opposite each other and leading in from the extreme lower end of casing B, extending through the screw threaded portion of the inlet opening 19. A duct 22 is provided in the supporting casing B leading from the lubricating reservoir 11 downwardly at an acute angle and leading into the passageway 14 provided in the casing B.

The spindle C may be of the ordinary type of spindle tapering outwardly toward both ends from its central portion, and adapted for axial disposition in a passageway 24 of the whirl D. The spindle C, is in fact, welded or otherwise secured in this passageway, whereby the spindle C and whirl D are rigidly connected. The upper portion 25^a above the whirl D is adapted for receiving a bobbin or the like for the spinning of yarn, thread, or the like thereon. The lower portion 25 of spindle C, which depends below

105

110

the whirl D, is provided for insertion in the casing B in a manner to be subsequently set forth. The extreme lower end 26 of the portion 25 of spindle C is recessed upwardly 5 to provide a bearing point for suspending the spindle C and whirl D in the manner to be subsequently set forth. The whirl D may be of the ordinary type, including the belt receiving portion 27, intermediate the 10 lower and upper circumferential flanges 28 and 29 respectively. The whirl head 30 is provided, above the flange 29, and having suitable ribs 31 thereon for engaging the bobbin. The annular flange or circumferential portion 28 of the whirl D is preferably provided with a depending bead 32, extending annularly upon the bottom face thereof, and upon the outer marginal edge. A socket recess 34 is provided extending axially and upwardly in the whirl D from the bottom flange 28, and for the free reception 15 of a portion of the casing B therein.

The bolster E is of novel formation, and is provided for insertion into the casing 25 B from the screw threaded end 19 of said casing B, and adapted for receiving the depending portion 25 of spindle C. This bolster E includes an upper cylindrical portion 36, and a lower cylindrical portion 37, 30 said portion 37 being of greater external diameter than the portion 36 to provide a shoulder 38 at the juncture of said portions 36 and 37. A tapering bore or passageway 40 is provided axially through the upper 35 and lower portions 36 and 37 of the bolster E, and in fact adapted for reception of the lower portion 25 of the spindle C when the same is assembled therein. A groove 41 extends longitudinally of the lower cylindrical portion 37, and is provided as an oil passageway intermediate the casing B and outer surface of the bolster E, when said bolster is assembled in the casing B. Suitable radial apertures or ducts 42, are provided, in the groove 41, which extend and communicate into the passageway 40. Various other radial ducts 43 are provided in the portions 36 and 37 to communicate between the exterior and interior of the bolster 45 E. The extreme lower marginal end 44 of the enlarged portion 37 of bolster E is provided with adjacent lugs 45^a, extending diametrically opposite on the exterior surface of the portion 37, and adapted for sliding 50 in the slots 20 of the casing B in a manner to be subsequently described. The adjusting means F of the spindle mechanism includes the member 45, which is in reality a screw threaded plug having the screw 55 threaded shank portion 46 thereof for engagement upwardly in the screw threaded aperture of the casing E, the plug 45 having an exterior knurled head 47 for manual adjustment of the same. The inner and top 60 surface of the shank portion 46 is provided

with an arcuate seating depression 48 for receiving a ball bearing element 49. Suitable washer elements 50 of a predetermined thickness and gauge are provided intermediate the head 47 of the adjustable bearing 45, and the lower marginal end of the casing B, in order to accurately gauge the adjustment of the plug 45 in the casing B. 70

In assemblage, the bolster E is properly inserted in the passageway 14 of the casing B, the reduced or smaller portion 36 of said bolster E being first inserted through the screw threaded opening 19, and positioned in such manner that the lugs 45^a slide upwardly in the slots 30 through the screw 75 threaded portion 19 of casing B. The plug or step bearing 45 is next adjusted, as above described, in the casing B, and whereby the bolster E is supported upon the upper face of the shank 46. The bearing member 49 is 80 of course, disposed axially of passageway 40 of the bolster E, and extends upwardly in said passageway and free from contact of the sides thereof. The spindle C is next 85 assembled to the casing B as above described, and whereby the lower portion 25 thereof is properly inserted through the upper opening 13 of casing B and extends into the passageway 40 of the bolster E, the lower bearing end 26 of said spindle C resting 90 upon the ball bearing 49. The bearing collar 51^a welded or otherwise rigidly mounted on the spindle C within the whirl socket 34 also bears in the marginal groove 52^a on the upper end of bolster E. In this 95 position, the whirl D will be suspended over the casing B, and whereby the upper end 12 of said casing B extends into the depression or socket 34 of the whirl D. In this position, the annular flange 28 is spaced just above 100 the lubricating reservoir 10 and acts as a cover therefor. The annular bead 32 depends circumferentially about the upper marginal edge of the lubricating reservoir 11, and consequently prevents dust and the 105 like from entering in said reservoir 11. The nut 45 is properly adjusted in the casing B, whereby the entire weight of the spindle E and whirl D is borne by the anti-friction or ball bearing member 49, and the bolster F. 110 The depending portion 25 of the spindle C, of course, rotates in the bolster E, although there is very little clearance intermediate the elements. Due to the lugs 45^a, the bolster E will be prevented from rotating relative to 115 the casing B.

When removing the bobbin from the spindle C, said spindle C and whirl D are apt to ride relative in the casing B, due to the speed at which the same are rotated. To 120 prevent disconnection of the spindle C and whirl D from the casing B, a pawl or dog element 55 is provided, having an upper tooth 56 adapted for engaging the upper surface of the annular flange 28 to limit or 125

define the movement of the spindle C with respect to the casing B. An outwardly projecting arm 57 is provided whereby the pawl 55 may be rocked upon a pivot 58, for 5 moving the tooth 56, whereby the entire spindle element C and whirl D may be removed. The pivot element 58 which supports the pawl 55, is supported by the radial ears or lugs 60, whereby the pawl 55 is supported intermediate said lugs 60 and with 10 just sufficient friction that the pawl 55 may maintain any position in which the same is manually placed. Normally, the tooth 56 of pawl 55 is spaced outwardly from the belt 15 engaging surface 27 of the whirl D, by the belt (not shown), which engages the portion 27 and will not come into contact with the pawl 55.

A lifting element 62 is provided pivoted 20 to the pin 58 which supports the pawl 55, for lifting the whirl D and the spindle C, whereby the lubricating reservoir 11 may be uncovered for access to the interior thereof for refilling purposes. The lifting lever 25 62 preferably includes a pair of spaced arms 63 and 64, provided upon their outer free ends with heads 65, which engage diametrically opposite sides of the head 10 and normally rest just beneath the bead 32 of the 30 cover flange 28 of whirl D. The arms 63 and 64, are in fact pivoted to the pin 58 adjacent the outer sides of the lugs 60, said arms 63 and 64 having a bight portion 67, which in fact is a hand or finger engaging 35 lever extending outwardly and just below the finger engaging portion 57 of pawl 55, to facilitate operation of the lifting device 62.

Waste or some other absorbent material 69 40 is placed in the lubricating reservoir 11, for retaining a sufficient amount of lubricant for lubrication of the spindle mechanism. The lubricant flows into the passageway 14 through the duct 22, where the same flows 45 freely about the outer surface of the upper portion 36 of bolster E, since the same is spaced from the inner sides of the passageway 14, due to the enlarged cylindrical portion 37 of said bolster E. The lubricant 50 flows through the various ducts 43 and down through the groove 41 through the various ducts 42 therein and properly lubricates the point bearing 26 of spindle C.

The adjusting mechanism F has been provided 55 to compensate for wear upon point 26 of spindle C, and on bearing collar 51^a and in marginal groove 52^a. This wear will, of course, be very minute. To maintain an accurate adjustment, the very thin and accurately gauged washer elements 50 are provided, for securing a proper adjustment.

From the foregoing it can be seen that a spinning spindle has been provided, in which the parts thereof are of practical construction, and can be assembled in accurate

and easy manner to perform the purpose for which the same is provided. The bolster E, is of course, adjusted with the spindle C. The lubricating system and arrangement of parts to facilitate supplying of lubricant to 70 the reservoir 11 are of novel construction, and provided to simplify operation.

Various changes in the shape, size and arrangement of parts may be made to the form of the invention herein shown and described, 75 without departing from the spirit of the invention or the scope of the claims.

I claim:

1. A spinning spindle comprising a casing, a spindle, and a bolster for said spindle, 80 said spindle adapted for insertion in one end of said casing, the bolster adapted for insertion in the other end of said casing.

2. A spinning spindle comprising a casing open at both ends, a spindle adapted for insertion in one end of said casing, a bolster for insertion in the other end of said casing to receive the spindle, and retaining means for said bolster. 85

3. A spinning spindle comprising a casing open at both ends, a spindle adapted for insertion in one end of said casing, a bolster for insertion in the other end of said casing to receive the spindle, and adjustable retaining means for supporting said bolster and 90 spindle. 95

4. A spinning spindle comprising a casing provided with an upper opening, and a lower screw threaded opening, said screw threaded opening having slots therethrough 100 extended axially of the casing, a bolster for reciprocation within the casing and adapted for insertion from the screw threaded opening therein, said bolster having lugs extending therefrom for sliding in the slots of said casing to prevent rotation therewith; a spindle for insertion into said bolster and casing from the upper opening in said casing; and an adjustable step plug for engaging in the screw threaded opening of said casing for 110 adjustably supporting said bolster and spindle. 115

5. In a device of the class described, the combination of a supporting casing provided with a lubricating receptacle therein, 115 a spindle rotatable within said casing, means movable on said casing for normally closing said lubricating receptacle, and means pivoted on said casing for moving said first mentioned means for access to said lubricating receptacle. 120

6. A device of the class described comprising a supporting casing including an oil reservoir, spindle means mounted in said casing for rotation therein and adapted to 125 normally close said oil reservoir, and means carried by said casing to facilitate lifting of said spindle means to have access to said reservoir independent of whether the spindle means is stationary or rotating. 130

7. A device of the class described, comprising a supporting casing including a lubricating reservoir, a spindle, cover means for said lubricating reservoir, and an arm 50 movable on said casing for adjustment of said cover means to remove the same from said reservoir for access thereto.
8. A device of the class described comprising a supporting casing having an oil 10 reservoir thereon, for feeding oil into the interior of said casing, a spindle bearing in said casing, a whirl rigid with said spindle and normally covering said oil reservoir, and means carried as a part of said 15 device for raising said whirl and spindle for access to the reservoir.
9. In a device of the class described, the combination of a casing including a lubricating reservoir provided with a duct there- 20 in to the interior of said casing, a spindle, a whirl rigid with the spindle and including a flange thereon provided as a cover for said reservoir, and an arm pivoted to said casing for adjustment of said whirl flange for ac- 25 cess to the oil lubricating reservoir.
10. In a device of the class described, the combination of a casing, an oil reservoir 30 therein for feed of oil into said casing, a spindle including a whirl rigid therewith, a portion of said whirl provided as a cover for said casing reservoir, an arm on said casing for limiting the movement of said spindle, and an arm pivoted to said casing for operation of said whirl to raise the same 35 from said casing reservoir.
11. In a device of the class described, the combination of a casing including a lubricating reservoir, a bolster provided for insertion in said casing to have a circum- 40 ferential clearance for the major length thereof with respect to said casing and for receiving a body of lubrication, and a spindle, said bolster having connecting ducts therein.
12. In a device of the class described, the combination of a casing, a spindle, a whirl rigid on said casing and including a flange, said casing provided with an oil reservoir 45 normally covered by said whirl flange, and a lifting element including a pair of rigidly connected arms pivoted to said casing and adapted for normal contact beneath a portion of said whirl covering said reservoir, whereby upon manual operation of said lifting element the reservoir will be 50 uncovered for access thereto.
13. As an article of manufacture, a bolster for spindles of cylindrical formation including a portion which is of less diameter than the remaining portion, the portion of greatest diameter having a groove extending longitudinally thereof inwardly of the exterior surface thereof, said bolster having a longitudinal passageway therein, and ducts leading transversely thru the portion of greatest diameter to connect said longitudinal groove with the passageway of the bolster.
14. A device of the class described comprising a casing having a passageway there- 70 through, and a slot extending upwardly within the casing from the lower end thereof, a hollow cylindrical shaped bolster adapted for insertion within the casing from the lower end thereof, said bolster having a laterally extending lug at the lower end thereof adapted for sliding within the slot of said casing, a spindle for rotation within said bolster, and means for supporting the bolster at the lower end of said casing.
15. A device of the class described comprising a casing providing a passageway therein open at both ends of the casing, a bolster adapted for insertion from the lower end of the casing in such manner as to prevent rotation of the bolster within the casing, a spindle, a whirl rigid with the spindle, said spindle adapted for rotation within the bolster so that the whirl passes over the upper end of said casing, an adjustable support and bearing for the bolster and spindle carried at the lower end of said casing, means carried by said casing to limit the amplitude of longitudinal movement of the 85 whirl and spindle thereon, and means carried by said casing for lifting the whirl and spindle upwardly upon said casing.

MIKEL LAVIGNE.
